COOLER

Roy E. Buvinger, Dayton, Ohio

Application February 17, 1938, Serial No. 191,021

12 Claims. (Cl. 259—122)

This invention relates to improvements in coolers of a type that may be applied to the top of a can or container and spray around the can or container a liquid.

5 It is more particularly the object of this invention to provide an instrumentality that may be placed over the mouth of the container and distribute about the container and over the surface thereof a liquid and break the liquid up into fine sprays and cause these fine sprays to impinge upon the surface of the container.

10 It is also the object of this invention to provide a cooling instrumentality operated by a source of water under pressure, to atomize the water, distribute the water about the surface of a container containing a material to be cooled and agitate the material to be cooled so as to bring various parts of said material into contact with the inner surface of the container.

15 It is also an object of this invention to provide in connection with a container an instrumentality that may be operated by water under pressure and which will atomize the water and distribute the atomized water over the surface of the container and at the same time agitate the material within the container so that the material in the container will be brought in contact with the inner surface of the container by means of a current produced therein.

20 These and other advantages will be apparent from the following description taken in connection with the drawings, in which:

25 Figure 1 is a vertical section through the cooler and the top of a container shown in dotted lines.

Figure 2 is a bottom plan view of the cooler.

30 Figure 3 is a top plan view of an annular base member.

Figure 4 is a section on line 4—4 of Figure 3.

35 Figure 5 is a segment taken from the base member on the lines 5—5 of Figure 3.

Figure 6 is a top plan view of a rotor adapted to rotate within the annular base member.

40 Figure 7 is a side elevation of the rotor shown in Figure 6 with its supporting and rotating shaft shown in section.

Figure 8 is a bottom plan view of the rotor.

45 The cooler as a whole is composed of four parts: An annular base member 1, an inner support member 2, a cap member 3, and a rotor 4, which is somewhat bell-shaped. The base member, the support member, and the cap member form a housing, the lower part of which housing forms an annular water chamber. The annular base member consists of a horizontal part 5 and

a vertical flange 6. Extending upwardly from the inner edge of the base member is a plurality of projections 7, slightly spaced apart to provide notches 8 through which water or other cooling fluid is sprayed. Extending outwardly from many of the projections 7 toward the flange 6 are fins 9, which are arranged at an acute angle to the radii of the base member. Each fin adjacent its projection 7 is reduced in size so that it extends above the inner surface of the horizontal part 5 only a small distance. This reduced part of each fin is indicated by the numeral 10. The annular member is provided with a plurality of bosses 11 with screw holes 12 therein to receive screws 13 by which the support member 2 may be attached to the annular member 1. For receiving these screws, the support member is provided with bosses 14. For the purpose of introducing water into the cooler the flange 6 has therein an opening 15 into the water chamber, around which is an inlet spout 16 arranged to project at an acute angle to the radius of the base member passing through the opening 15. Extending from the upper edge of the flange 6, is a plurality of bosses 17 with holes 18 therein. The support member has an inner downwardly extending spout 19, adapted to fit within the mouth of the container such as a milk can to support the whole cooling apparatus on the container. Extending from the top edge of the spout 19, the support member has an outwardly and downwardly extending part 20 with arcuate slots 21 therein adjacent spout 19. The outer part of the support member consists of a vertical wall part 22 adapted to engage the base member at the parts 10 between the projection 7 and the fins 9. In this structure there is provided small passageways between the annular member and the support member at the lower parts of the notches 8. On the part 20 of the support member and between the spout 19 and the vertical wall part 22 are equally spaced ribs 23 which have notches 24 therein which serve to stabilize and position the cooler on top of the container or can, such as a milk can.

45 The cap member 3 has an annular flange 25 adapted to fit within the flange 6 of the base member and has an overhanging lip 26 which engages and extends over the upper surface of the annular flange 6. For the purpose of attaching the cap member to the annular base member there is provided on the cap member a plurality of lugs 27 with holes therein to receive screws 28 which are threaded into the holes 18 of the lugs 17 on the base member. The flange 55

25 is provided with a notch 29 opposite the opening 15 so as to provide a passageway from the spout 16 into the cooler. The central part of the cap member 3 is depressed as indicated by 5 the numeral 30 and has therein a central opening 31 around which there is an upwardly extending flange 32 and a horizontal flange 33. These flanges provide a support for one member 34 of a raceway. The cap member 3 in the depressed part has a plurality of slots 35 arranged around the flange 32.

Supported by the cap member and rotating between the cap member and the support member 2 is the bell-shaped rotor 4 which has an upwardly extending hollow stem 36 to which is securely attached a race member 37 which cooperates with the race member 34 to form a runway for balls 38. The rotor is thus rotatably supported by means of the cap member 3. The 10 hollow stem 36 is provided with a vertical passageway 39 through which extends a round shaft 40 which has a plurality of flattened portions 41 to receive a screw 42 by which the shaft may be rotated adjusted with relation to cap member 25 and the whole cooling apparatus. This adjustability is for purpose of adapting the cooler to cans of various sizes, such as, 3, 5 or 10 gallon cans. On the lower end of the shaft 40 are stirrer blades 43 which may be made of Bakelite 30 or any other suitable material and which is suitably attached to the shaft 40 which is made of stainless steel.

Extending horizontally from the hollow stem, there is a horizontal portion 44 of the stirrer 35 which passes into an annular decline portion 45 and into a vertical portion 46. In the horizontal portion of the stirrer there is a plurality of slots 47 and adjacent each slot is an arcuate rib 48. Each rib extends from the inner edge of one slot 40 to and about the outer edge of another slot and terminates adjacent to but spaced from an annular flange 49 at the outer edge of the horizontal portion of 44 of the rotor. This flange 49 extends around a flange 50 extending downwardly 45 from the cap member 3. The slots 47 and 35 serve as outlets from the container so that any heated air therein may readily escape. The parts 48, 49, and 50 act as baffles to prevent water or any other cooling liquid from passing into the 50 can or container through the spout 19. Around the outer surface of the vertical portions 46 of the rotor is a plurality of inclined blades 51 against which the liquid passing through the spout 16 impinges whereby the rotor is rotated. 55 These blades are arranged about one inch apart and serve to break the stream of water up as well as to rotate the rotor and further these fins are so arranged that they tend to force the water accumulating in the base member downward and 60 inward beneath the rotor through the notches 8 in fine sprays in which the water is separated into minute particles and are distributed over the outer surface of the can or container to which the cooler is attached. To conduct any water 65 that might accumulate in the upper edge of the space between the rotor and the cap member there is provided in the portion 45 of the rotor a plurality of troughs 52, each of which has an inwardly extending rib 53 on the inner side and 70 under of the portion 46. While the troughs 52 aid in returning water collecting between the cap and the rotor downward toward fins 51, the ribs 53 serve to prevent any water accumulating 75 between the rotor and the support member from passing into spout 19. The water accumulating

in the space between the rotor and the support member through the operation of these ribs passes back down to the bottom of the flange 46 or out through the slots 21 and around the outer surface of the container or can. 5

When the various parts of the cooling apparatus are assembled as shown in Figure 1 and the apparatus is connected to a source of water pressure by means of the spout 16 and the pressure is applied, the rotor is caused to rotate carrying with it the stirrer. The water which operates the rotor passes beneath the rotor through the notches 8 where it is divided into fine sprays and caused to impinge upon the surface of the can or container. This water being finely sprayed 15 upon the surface of the can tends to absorb heat more rapidly and the stirrer provides a current in the contents of the can, rather than an agitation of said contents.

It has been found from actual practice that, 20 when this cooler is applied to a can of milk, the temperature of the milk within the can may be reduced in fifteen minutes to within four degrees to the temperature of the water sprayed. It is also possible with the use of the present apparatus after the animal heat has been removed out of the milk to flash pasteurize the milk in the can by the use of hot water instead of the cold water. 25

This apparatus may be attached to the cans 30 and container of various sizes. Three adjustments have been shown but it is to be understood that the extent of the application of the apparatus is not to be limited in any manner by this showing. The degree of the agitation may be 35 varied by varying the pitch of the blades 43. It is not the purpose of this apparatus that the milk or other material be stirred but it is the purpose of this invention that the material be caused to move from the center of container to the surface 40 and from the surface to the center thereof.

Having described my invention what I claim as new and wish to protect by Letters Patent is:

1. In a cooler, a substantially bell-shaped rotor having therein a plurality of slots, fins arranged about said slots and peripheral fins on said rotor.
2. In a cooler, a bell-shaped rotor having therein a plurality of slots, arcuate ribs about said slots, an annular flange extending around said slots and arcuate ribs and radial extensions 50 around the periphery of said rotor.
3. In a cooler, in combination with a housing, a bell-shaped rotor mounted in said housing and rotatably supported thereby, said rotor having therein a plurality of slots arranged about its 55 point of support, and a plurality of ribs on said rotor, each rib extending from one slot to and about another slot and an annular flange surrounding said slots and ribs.
4. In a cooler, a housing having an inwardly 60 and downwardly extending annular flange, a rotor mounted within said housing and having an annular flange around the first named flange, blades on the rotor beneath the flanges, and means to admit fluid under pressure into the 65 housing against the blade whereby the rotor is caused to rotate, said flanges acting to prevent the upward movement of the fluid.
5. In a cooler, a housing having a downwardly 70 extending centrally disposed spout adapted to fit in a container, an inlet opening for a cooling fluid and a large number of small outlet openings adapted to direct the fluid in small horizontal streams about the container towards the spout, and means in the housing extending 75

through the spout and operated by the fluid to agitate any fluid in the container.

6. In a cooler, an annular base member having on its outer edge a flange, on its inner edge a plurality of projection forming notches, a fin for each projection located between the projection and the flange, a cap on the flange and a support member on the fins.

7. In a cooler, an annular base member having on its outer edge a flange, on its inner edge a plurality of projection forming notches, a fin for each projection located between its projection and the flange, each fin being reduced in size adjacent its projection, a cap on the flange and a support member on the reduced parts of the fins.

8. In a cooler, an annular base member having on its outer edge a flange provided with an inlet spout, on its inner edge a plurality of projections forming notches and a fin for each projection between the projection and the flange, each fin being reduced in size adjacent its projection, a cap member resting on said flange, and a support member fitting around the projections and resting on the reduced parts of the fins, so as to leave a small opening at the lower part of each notch.

9. In a cooler, an annular base member having on its outer edge a flange provided with an inlet spout, on its inner edge a plurality of projections forming notches and a fin for each projection between the projection and the flange, each fin being reduced in size adjacent its projection, a cap member resting on said flange, and a support member fitting around the projection and resting on the reduced parts of the fins, just above

the lower parts of said notches and a rotor supported by the cap member for rotation between the cap member and the support member just above the fins.

10. In a cooler, an annular base member having on its outer edge a flange provided with an inlet spout, on its inner edge a plurality of projections forming notches and a fin for each projection between the projection and the flange, each fin being reduced in size adjacent its projection, a cap member resting on said flange, a support member fitting around the projection and resting on the reduced parts on the fins, whereby small openings are provided by the notches beneath the support member, and rotor supported by the cap member for rotation between the cap member and the support member just above the fins, said rotor having operating blades.

11. In a cooler, a housing having a removable cap with an opening therein and a spout adapted to fit in a container, a rotor in said housing having a stem projecting through said opening and said spout, and an anti-friction support for said rotor, said support comprising a raceway member on the cap around said opening, balls on said raceway member and a raceway member on said stem resting on said balls.

12. In a cooler, a housing having an inlet opening for a cooling liquid and a plurality of horizontally disposed outlet openings for said liquid, and a rotor in said housing, said rotor having a portion adjacent said openings forming with the housing an annular passageway for directing the cooling liquid into an inwardly and horizontally moving sheet adjacent the outlet openings.

ROY E. BUVINGER.
